UNITED STATES PATENT OFFICE.

SAMUEL ALLEN GUIBERSON, JR., OF SAN FRANCISCO, CALIFORNIA.

CASING-ELEVATOR.

1,112,605.

Specification of Letters Patent.

Patented Oct. 6, 1914.

Application filed March 7, 1914. Serial No. 323,195.

To all whom it may concern:

Be it known that I, SAMUEL ALLEN GUIBERSON, Jr., a citizen of the United States, residing at the city and in the county of San Francisco and State of California, have invented certain new and useful Improvements in Casing-Elevators, of which the following is a specification.

My invention relates to that class of well-casing elevators in which opposing jaw-members, adapted to embrace the casing-pipe under its coupling collar, are provided at their free ends with an automatic locking means.

The object of my invention is to provide a casing-elevator of this type with a simple and effective automatic latch.

To this end my invention consists in the novel casing-elevator which I shall now fully describe by reference to the accompanying drawings, in which—

Figure 1 is a plan of my casing-elevator, partly broken, and showing it locked. Fig. 2 is a side view of the casing elevator looking at it from its latch side. Fig. 3 is a section on the line $x-x$ of Fig. 1.

1 is one jaw-member of the elevator and 2 is the other jaw-member. These are hinged together at one side on the pin 3.

4 are the suspension lugs of the elevator.

The free extremity of the jaw-member 1 is grooved or slotted out at 1' to receive the butt of a latch 5, which is pivotally mounted therein upon a cross bolt 6, carried by the jaw-member 1, the ends of said bolt, as shown in Fig. 2, being countersunk so as not to project beyond the top and bottom of the jaw, it being thereby out of the way when the elevator is set down on its flat supporting surface. The latch 5 is formed with a beveled head 7 having a catch shoulder 8. The free extremity of the other jaw-member 2 is rounded or beveled at 9 and is grooved out at 10, said groove having a catch shoulder 11. The groove 10, as seen in Fig. 2, is flared as shown at 10' both above and below, to provide ample room for the hand of the operator to reach the latch head 7 to release it.

12 is a spring to control the latch 5. This spring is carried on a fixed cross-pin 13 mounted in the jaw-member 1, and said pin serves, in conjunction with a notch 14 in the butt of the latch 5, to limit the movement of the latch and to define its position ready for use.

To open or unlock the elevator, the operator inserts his hand into the flaring groove 10 and pushes out the latch head 7, so that its catch shoulder 8 moves away from the catch shoulder 11 of the jaw member 2, whereupon said jaw member is free to swing open. The moment the latch 5 is released from the hand of the operator, the spring 12 throws it back into position ready for action again, this position being defined by the engagement of the notch 14 with the fixed pin 13.

To close or lock the elevator, the jaw-member 2 is swung toward the other jaw member, and as its beveled end at 9 contacts with the beveled head 7 of the latch it will force said latch back until its catch shoulder 11 passes by the catch shoulder 8 of the latch head, whereupon the latch will spring in and lock the jaw members together, as shown in Fig. 1. It will be seen that this construction of automatic latch, by being seated well within its grooved surroundings presents a practically solid and even side to the elevator, with no obstructing projecting lugs, flanges and other parts which are usually found in elevators of this type. This latch is also economical in manufacture in that there is very little machine work necessary, it being possible to use drop-forgings.

I claim—

1. A casing-elevator comprising opposing jaw-members having suspending lugs, said jaw-members being hinged together at one side, one of said jaw-members at its free extremity being grooved, and the other of said jaw-members having its free extremity grooved, beveled and shouldered; and a spring-controlled latch pivotally carried in the grooved free extremity of the first jaw-member, said latch having a beveled catch head adapted to enter and coact with the grooved, beveled and shouldered free extremity of the other jaw-member to automatically lock the two jaw-members together.

2. A casing-elevator comprising opposing jaw-members having suspending lugs, said jaw-members being hinged together at one side, one of said jaw-members at its free extremity being grooved, and the other of said jaw-members having its free extremity grooved, beveled and shouldered; a spring-controlled latch pivotally carried in the grooved free extremity of the first jaw-

member, said latch having a beveled catch head adapted to enter and coact with the grooved, beveled and shouldered free extremity of the other jaw-member to automatically lock the two jaw-members together, and means for limiting the latch to hold it in position for engagement.

3. A casing-elevator comprising opposing jaw-members having suspending lugs, said 10 jaw-members being hinged together at one side, one of said jaw-members at its free extremity being grooved, and the other of said jaw-members having its free extremity grooved, beveled and shouldered; a spring- 15 controlled latch pivotally carried in the grooved free extremity of the first jaw-member, said latch having a beveled catch head adapted to enter and to coact with the grooved, beveled and shouldered free ex- 20 tremity of the other jaw-member to automatically lock the two jaw-members together, and means for limiting the latch to hold it in position for engagement, consisting of a fixed pin in the first jaw-member 25 and a notch in the latch coacting with the pin.

4. A casing-elevator comprising opposing jaw-members having suspending lugs, said 30 jaw-members being hinged together at one side, one of said jaw-members at its free extremity being grooved, and the other of said jaw-members having its free extremity grooved, beveled and shouldered; a fixed bolt traversing the groove of the free ex- 35 tremity of the first jaw-member with its ends countersunk below the outer surfaces

of said jaw-member; and a spring controlled latch pivotally mounted on said bolt, said latch having a beveled catch head adapted to enter and to coact with the grooved, beveled and shouldered free extremity of the other jaw-member to automatically lock the two jaw-members together. 40

5. A casing-elevator comprising opposing jaw-members having suspending lugs, said 45 jaw-members being hinged together at one side, one of said jaw-members at its free extremity being grooved, and the other of said jaw-members having its free extremity grooved, beveled and shouldered; a fixed bolt traversing the groove of the free extremity of the first jaw-member with its ends countersunk below the outer surfaces of the said jaw-member; a spring controlled latch pivotally mounted 50 on said bolt, said latch having a beveled catch head adapted to enter and to coact with the grooved, beveled and shouldered free extremity of the other jaw-member to automatically lock the two jaw-members to- 55 gether, and means for holding the latch ready for use, consisting of the fixed pin in the first jaw-member and the notch in the latch coacting with the pin. 60

In testimony whereof I have signed my 55 name to this specification in the presence of two subscribing witnesses.

SAMUEL ALLEN GUIBERSON, JR.
